UNITED STATES PATENT OFFICE.

AMOS F. DIXON, OF NEW YORK, N. Y., ASSIGNOR TO WESTERN ELECTRIC COMPANY, OF CHICAGO, ILLINOIS, A CORPORATION OF ILLINOIS.

PANEL CONSTRUCTION FOR SWITCHBOARDS.

No. 918,513.

Specification of Letters Patent. Patented April 20, 1909.

Application filed April 26, 1908. Serial No. 429,170.

To all whom it may concern:

Be it known that I, AMOS F. DIXON, citizen of the United States, residing at New York, in the county of New York and State 5 of New York, have invented a certain new and useful Improvement in Panel Construction for Switchboards, of which the following is a full, clear, concise, and exact description.

This invention relates to selectors of a type 10 particularly intended for use in a so-called automatic or semi-automatic telephone exchange system, and its object is, in general, to provide an improved simple structure wherein a large number of individual 15 selectors are mounted compactly together in a bank, to permit the individual operating mechanisms to be conveniently driven from a common source of power, to permit easy assembly, adjustment and repair of the various 20 parts, and more particularly to simplify the wiring of the line terminals multiplied upon the different individual selectors, by constructing such multiple terminals in strips punched from sheet metal, the construction, however, being such as not unduly 25 to increase the inductive capacity effect between adjacent conductors.

I will describe my invention particularly 30 by reference to the accompanying drawings, wherein—

Figure 1 is a front view of a terminal board and the brush carriers or movable switch members of a bank of selectors to which such terminal board is common; Fig. 2 is an edge 35 view of the bank of selectors indicated in Fig. 1; Fig. 3 is a detail edge view of a portion of the terminal-board, and two of the selector brush-carrier rods or movable switch members traveling over the same, on a some- 40 what larger scale than Fig. 2; Fig. 4 is a detail front view of a portion of the board; Fig. 5 is a detail sectional view of a fragment of the terminal board, taken transversely to the terminal strips; and Fig. 6 is a sectional 45 plan view of a portion of the terminal board and some of the co-operating movable switch members.

Like parts are designated by similar characters of reference throughout the several 50 views.

Each selector comprises a selectively-controlled operating or "elevator" mechanism 40, a movable switch member 50 operatively-connected thereto, and a row of stationary line terminals upon the common terminal 55

board. As shown, the elevator mechanisms of the various individual selectors are mounted close together at the top of the common terminal board, and are connected by flexible cords 54 to their respective movable switch 60 members or brush-carriers, which are shown as rods 50 arranged to slide vertically in guides 55 before the face of the terminal board.

The board shown has its terminals arranged in five horizontal zones, and each selector rod has five sets of brushes, one for each zone. The selectors illustrated are intended for three-wire switching and there are therefore three brushes 51, 52, 53 in each set, 65 the line terminals being correspondingly arranged in sets of three; but it is evident that any other desired grouping may be employed.

The terminal board is built up in sections 75 or units 41 supported at the ends by upright posts 42 of the main framework. Each section is secured individually at each end to a separate supporting lug 43 which is adjustably mounted upon a post 42, so that each 80 section may be removed adjusted or replaced independently of the others. Each section or unit of the terminal board comprises a block of insulating material having narrow horizontal parallel grooves in its surface, receiving narrow line-terminal strips 44 which may be punchings of sheet metal having ears or lugs projecting therefrom to form the contact terminals 61, 62, 63, with which the brushes 51, 52, 53, respectively, are adapted to 85 engage. These ears or lugs upon the superposed metallic strips thus form multiple rows of terminals, one row for each selector mechanism, each metal strip having a lug or multiple terminal for each selector. As all the 90 multiple terminals of a given conductor for a large number of selectors may thus be constructed in a single strip, it will be seen that the wiring for the bank of selectors is a comparatively simple matter as compared with 95 the old plan of separately wiring each terminal. If multiple terminals of the same line are required upon both sides or faces of the board, a terminal strip on one side may be connected to its mate on the other side by a 100 short jumper wire 66 passing through a transverse hole in the board as shown in Fig. 6.

The line terminal strips 44 when embedded in the slots or grooves in the terminal board are held in place by an insulating compound 110

65 such as thick varnish, applied in a soft or semi-liquid state, said compound when hardened serving to hold the strips and their lugs rigidly in position.

5 I am aware that it has been proposed heretofore to construct a bank of terminals from alternate strips of metal and insulating material, piled up one above the other to form a unitary structure, the metal strips having 10 multiple ears or contact lugs projecting on both sides of the panel thus built up. In a terminal board so constructed, however, the mutual capacity effect between adjacent conducting strips is undesirably high, due to 15 the large surface area necessary to permit the piling of the conducting strips. In the structure of my invention, this objection is largely overcome, the conducting strips being very narrow, offering but little larger electro- 20 static area than an ordinary wire. Indeed, the strips, instead of being punched from sheet metal, may be formed up from lengths of wire having loops at intervals to form the projecting contact lugs.

25 My invention permits of a decrease in the electrostatic area of the conducting medium to such an extent that the accumulative charge on the surface of the conductors may be dissipated by grounding one of the three 30 terminal strips forming the conductors individual to a line.

35 My invention has the advantage of a minimum transmission dissipation and elimination of mutual disturbances between lines. The path to ground from the third terminal 40 of each set may be obtained through the battery which is connected therewith, in ordinary systems, or through relays or other apparatus having comparatively low inductance. The terminal-board of my invention is moreover cheaper and easier to construct than the other.

45 The construction of the terminal-board herein described permits both sides of the board to be used for the accommodation of traveling switch members of selectors. A compact arrangement of the elevator mechanisms is provided for by the supporting frame shown, which has two platforms for 50 supporting these mechanisms, said platforms being mounted one above the other and the elevator mechanisms mounted thereon in staggered relations. That is to say, the elevator mechanism for one brush-carrier 55 rod will be mounted, say, on the upper platform, while that of the mechanisms for the next adjacent rod will be on the lower platform, and so on, giving space for the accommodation of a large number of elevator mechanisms 60 to permit their respective brush-carrier rods to be located at close intervals along the terminal board. This manner of constructing and mounting the various parts of the bank of selectors permits a large group 65 of operating or elevator mechanisms to be

conveniently driven from a common source of mechanical power. As shown, a motor-driven shaft 45 is suitably geared to each of the elevator mechanisms along the whole length of the terminal board on one side; a 70 similar shaft 45 being geared to the elevator mechanisms for the other side. It is understood that each elevator mechanism has a clutch by which its operating shaft carrying its elevator sheave 71 may be coupled with 75 or uncoupled from its power shaft, which is geared to the continuously-rotating motor-driven shaft.

I claim:

1. A selector-switch terminal board having shallow grooves in its face, narrow strips of sheet metal embedded edgewise in said grooves, each strip having projecting ears at intervals along its length adapted to be engaged by contact brushes of different 85 selectors, and insulating material flowed over the board and into said grooves and hardened.

2. A bank of selectors comprising a common terminal board having multiple sets of 90 line terminals in parallel rows, movable switch members for the individual selectors, arranged to travel over the different rows of line terminals, operating mechanisms for the individual selectors, each being operatively 95 connected to its corresponding switch member, and means for supporting said operating mechanisms in staggered relations, whereby the movable switch members may be set at close intervals along the terminal-board. 100

3. A bank of selectors comprising a vertical terminal-board having multiple line-terminals on both sides thereof, arranged in vertical rows, a supporting frame for said terminal-board, superposed platforms supported by said frame above said terminal-board, elevator mechanisms of the individual selectors, supported upon said platforms in staggered relations, and a common source of 105 mechanical power connected to said elevator mechanisms to operate the same. 110

4. A terminal-board comprising end-posts, board-sections or units of insulating material individually-secured at their ends to said posts, so as to be independently-removable, 115 said units being superposed to form a continuous surface, each unit having parallel grooves in its face, and line-terminal strips embedded in said grooves, each of said strips having projecting lugs at intervals along its 120 horizontal length forming multiple contact-pieces, the board being thus equipped with vertical rows of terminals which are multiple of one another.

In witness whereof, I hereunto subscribe my name this 17th day of April A. D., 1908.

AMOS F. DIXON.
